CLAIM

The ornamental design for a beard trimmer as shown and described.

DESCRIPTION

FIG. 1 is a perspective view showing a beard trimmer;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof; and,
FIG. 7 is a bottom view thereof.

The broken lines in the figures depict portions of the beard trimmer that form no part of the claimed design.
